SULPHONIC COMPOUND

Frederick H. MacLaren, Calumet City, Ill., assignor to Standard Oil Company, Chicago, Ill., a corporation of Indiana

No Drawing. Application November 25, 1931,
Serial No. 577,379

3 Claims. (Cl. 260—159)

This invention relates to sulphonic acids and it pertains more particularly to sulphonic acids and soaps prepared from particularly heavy unsaturated hydrocarbons.

The object of my invention is to prepare sulphonic compounds, either acids or soaps, which are particularly suitable for use as wetting agents, emulsion breakers, fat splitting agents, soluble oils, textile oils, etc. A further object is to utilize by-products of petroleum refining in the preparation of valuable sulphonic derivatives.

Other objects will be apparent as the detailed description of my invention proceeds.

I have discovered that heavy petroleum oils which have been subjected to a preliminary oxidation or cracking are particularly susceptible to sulphonation and that they yield sulphonic compounds which are exceptionally suitable for the uses above stated. Preferred stocks are pressure tar distillate, pitch still distillate, and the distillate obtained in the destructive distillation of heavy residual oils to form coke. The invention will be more clearly understood from the following detailed description of preferred embodiments.

Large amounts of gasoline are prepared by so-called cracking processes wherein heavier petroleum hydrocarbons such as gas oil are subjected to temperatures of about 850 to 900° F. under pressures of about 300 pounds, it being understood, of course, that these temperatures and pressures may vary within wide limits to fit the needs of petroleum cracking stocks and to operate in vapor phase or liquid phase to produce the desired end products. In all cracking processes, however, a part of the petroleum is converted into heavier products; these products may contain heavy unsaturated oils and tarry material and they are commonly called pressure tar. According to usual practice, the more volatile components thereof are evaporated and removed from the tar which is then useful for fuel, road oil, etc. On attempting to sulphonate this product with strong or fuming sulphuric acid, only coky products are obtained, together with copious quantities of sulphur dioxide gas. I have found, however, that if this material is distilled, the distillate can be readily sulphonated to give good yields of sulphonic acids with very little formation of coky matter. A distillate having an initial boiling point of about 450° F. or higher is particularly adaptable for the practice of my invention.

Pressure tar distillate having a boiling point above 450° F. may be sulphonated with fuming 55 104½% sulphuric acid, using about one to eight

pounds of acid per gallon. I prefer to maintain the temperature below 100° F.; the temperature may be as high as 170° F. but high temperatures are likely to yield coke or undesirable hard tarry products. The heavy distillate from pressure tar may be introduced into a cooled mixer and the acid may be added thereto with stirring at a rate sufficiently low to keep the temperature within the desired range. I have found that there is an almost instantaneous reaction and that large 10 yields of sulphonic compounds are obtained.

After the sulphonation I may steam the products to separate dilute sulphuric acid therefrom and thereby minimize the amount of salt formed by subsequent neutralization.

I then neutralize the acids with sodium hydroxide after which I extract with 50% alcohol. The products may be purified by extracting with more concentrated alcohol or in some cases the salts may be left in the soap to increase the effectiveness thereof. The soap may be dried to give a friable powder or fluffy mass which is hygroscopic and which has an alkaline reaction.

Instead of using a heavy distillate from pressure tar I may use a heavy distillate from coking stills producing coke by a cracking distillation of crude residuum. My invention makes use of the components having a boiling point above 450° F. or, in other words, I use the heavy unsaturated overhead products which are extensively cracked but free from tarry material. This heavy overhead from the coker may be sulphonated in the same manner as the overhead in the pressure distillate.

As another embodiment of my invention I may use the heavy unsaturated distillates obtained by reducing viscous residues to asphalt. When a petroleum oil is heated at high temperatures for the production of asphalt a certain amount of cracking takes place and I have discovered that the unsaturated distillates boiling above 450° F. are particularly adaptable for sulphonation. As above described this distillate may be a fraction of the so-called pitch still distillate or it may be a fraction of the distillate from the oxidation of heavy residual oils at high temperatures to yield asphalt. The heavy distillates above described give unusually high yields of sulphonic compounds. For example, when an ordinary straight run distillate having an initial boiling point of about 450° F. is treated with fuming sulphuric acid only about 15% of sulphonic compounds are formed. When a pressure tar distillate of the same boiling range was sulphonated the yield of sulphonic compounds was 55%. Yields from 55

pitch distillate may be over 70% and the overhead from the coker likewise gives a very high yield.

It should be noted that my process completely eliminates coke and tarry material from the sulphonic compounds. This is extremely important, particularly in connection with the purification and separation of the sulphonlic acid products.

While I have described preferred embodiments of my invention, it is understood that I do not limit myself to the treatment with 104½% sulphuric acid, and that variations in temperature, pressure, proportions, etc. may be made without departing from the invention.

I have found that chlorosulphonic acid may be used instead of fuming sulphuric acid and that the yields produced thereby are even higher than those produced by the sulphuric acid. Also I may extract the soaps or sulphonlic compounds with

chlorinated solvents such as carbon tetrachloride, chloroform, etc. but alcohols are preferred.

The hydrocarbons which are sulphonated in accordance with my invention may be characterized by the following properties:

Sulphuric acid absorption 12.0% to 20.0%
Hexane solubility 99.8% to 100.0%
Carbon residue 0.1% to 0.5%

As above stated, they give remarkable yields of sulphonlic compounds having highly desirable properties.

I claim:

1. The method of preparing sulphonlic compounds which comprises heating a petroleum oil to about 850-900° F. to cause it to be cracked, separating from said cracked petroleum oil all components having a boiling point below 450° F.,

separating from the remaining cracked petroleum composition all matter convertible into coke on sulphonation, leaving a clean unsaturated high boiling hydrocarbon oil characterized by a sulphuric acid absorption of about 12% to 20%, a hexane solubility of about 98.8% to 100% and a carbon residue of about .1% to .5%, and sulphonating said clean unsaturated high boiling hydrocarbon oil.

2. The method of preparing sulphonlic compounds which comprises heating a petroleum oil to a cracking temperature to cause the formation of unsaturated hydrocarbons and tarry matter, separating from said heated mixture all components having a boiling point below 450° F., distilling the remaining components to remove clean unsaturated high boiling hydrocarbons from tarry, asphaltic and coke-forming materials, and sulphonating the distillate which is characterized by an initial boiling point of at least 450° F., by a sulphuric acid absorption of at least 12%, a hexane solubility of at least 99.8%, and a carbon residue of less than .5%.

3. The method of preparing sulphonlic compounds which comprises heating a petroleum oil to about 850-900° F. whereby the oil is cracked and gasoline, gas oil and pressure tar are formed, separating the gasoline and gas oil from said pressure tar, distilling from said pressure tar all material having products boiling below 450° F., subsequently distilling from said pressure tar a high boiling unsaturated hydrocarbon oil which is substantially free from matter convertible to coke on sulphonation, and sulphonating said heavy pressure tar distillate.

FREDERICK H. MACLAREN.
